UNITED STATES PATENT OFFICE.

THOMAS D. HURLEY, OF GREEN ISLAND, NEW YORK.

ELECTRIC IRON.

1,202,846.

Specification of Letters Patent. Patented Oct. 31, 1916.

Application filed June 2, 1916. Serial No. 101,385.

To all whom it may concern:

It is known that I, THOMAS D. HURLEY, a citizen of the United States of America, and resident of Green Island, in the county 5 of Albany and State of New York, have invented certain new and useful Improvements in Electric Irons, of which the following is a specification.

This invention relates to electric irons 0 and particularly to means for attaching the terminal plug to electrically connect the conductor to the iron, the said invention having for its object the provision of novel means for manipulating the plug for the purpose 5 of withdrawing it from the terminal on the iron and also for supporting the iron on its end when the plug is in place on the terminal of the iron, the said plug being quickly removable so as to prevent undue arcing of 0 the current when the plug is removed.

With the foregoing and other objects in view, the invention consists in the details of construction, and in the arrangement and combination of parts to be hereinafter more 5 fully set forth and claimed.

In describing the invention in detail, reference will be had to the accompanying drawings forming part of this specification, wherein like characters denote corresponding 0 parts in the several views, and in which—

Figure 1 illustrates a view in elevation of the iron and plug with a fragment of a conductor; Fig. 2 illustrates an enlarged detail view of the said plug and a fragment of the conductor; Fig. 3 illustrates a plan view of the plate; and Fig. 4 illustrates an edge view thereof.

In these drawings 5 denotes the body of the iron, 6 the handle and 7 the handle bracket by which the handle is connected to the iron. The bracket 7 has an aperture 8 for the reception of a tongue 9 carried by the plug 10 and the said plug is intended to fit on the terminal 11 projecting from the body 5 of the iron. The body of the iron is further supplied with an outwardly extending arm 12 which constitutes one of the supports of the iron when it is placed on end whereas the iron is further supported by the 45 curved end 13 of the plate 14, which plate is secured to the plug 10.

As shown in the drawing the plate 14 has a plurality of apertures 15 to receive fastenings 16 by which the plate is secured 55 to the plug and the curved end 13 of the said plate is effective for use as a support for the iron when the said iron is placed in the position in which it is shown in Fig. 1, or the said curved end may constitute a hook 60 or pull to be engaged by a finger of an operator for the purpose of withdrawing the plug from the terminal.

I claim—

An iron having a support, and a terminal, 65 a handle bracket having an aperture secured to the iron, a plug having a projection fitting in the aperture of the handle bracket, and a plate secured to the plug, said plate having a curved end constituting a finger 70 engaging member and a coacting support for the iron when said iron stands approximately vertically.

THOMAS D. HURLEY.
